BACK PLATE FOR DRAWER PULLS AND THE LIKE

William Doyle Watt, Jr., Grand Rapids, Mich., assignor to Keeler Brass Company, Grand Rapids, Mich.

Filed May 14, 1962, Ser. No. 70,112

Term of patent 14 years

(Cl. D50—6)

FIG. 1 is a front view of a back plate for drawer pulls and the like embodying my new design; the eagle-like motif ornamentation is intaglio.

FIG. 2 is a top edge view.

FIG. 3 is a fragmentary rear view thereof, the remaining rear side being substantially the same as the portion disclosed.

FIG. 4 is a vertical section on a line corresponding to line 4—4 of FIG. 1.

I claim:

The ornamental design for a back plate for drawer pulls and the like, as shown and described.
